UNITED STATES PATENT OFFICE.

EDWARD C. FOWLER, OF FORESTVILLE, CONNECTICUT, ASSIGNOR OF ONE-HALF TO WILLIAM E. SIMONDS, OF CANTON, CONNECTICUT.

NAIL-PULLER.

SPECIFICATION forming part of Letters Patent No. 700,756, dated May 27, 1902.

Application filed June 3, 1901. Serial No. 62,871. (No model.)

To all whom it may concern:

Be it known that I, EDWARD C. FOWLER, a citizen of the United States of America, residing at Forestville, in the county of Hartford and State of Connecticut, have invented a certain new and useful Improvement in Nail-Pullers, of which the following is a description, reference being had to the accompanying drawings, wherein—

10 Figure 1 is a perspective view of a nail-puller embodying said improvement. Fig. 2 is a side view or elevation of the same nail-puller in position for operation. Fig. 3 is a side elevation view of the same nail-puller with the jaws entered into the wood and embracing the head of a nail preparatory to the extraction of the same. Fig. 4 is a side elevation view of the same nail-puller in the position where the nail is partially extracted.

20 The object of the improvement is an improved construction of a device in the nature of a nail-puller.

In the accompanying drawings the letter *a* denotes what may be termed the "frame" of the device. It is in two correspondingly-shaped parts, which may well be struck out of sheet-steel. They are united by rivets *a'*.

The letter *b* denotes a jaw which is fixedly attached to the frame. It is a piece fastened 30 between and to the two parts of the frame by rivets, as shown.

The letter *c* denotes a movable jaw which is pivotally attached between and to the two parts of the frame by means of the pivot *c'*. This movable jaw has an upper end adapted 35 for being beaten upon by a hammer, wherefore it is termed "anvil-headed." The movable jaw is provided with what may be called a "claw-hammer" hold, composed of the pins *c²* *c³*, projecting laterally from each side of the movable jaw.

The letter *d* denotes a filling-piece which is fastened to and between the two parts of the frames by rivets. It carries the foot *d'*, pro-

jecting laterally beyond the two sides of the frame, and is, by preference, curved on its lower surface.

The manner of using the device for extracting a nail is indicated in the drawings. First the jaws are set astride of the head of the nail which is to be extracted, as shown in Fig. 2. Then by means of a hammer beating upon the upper anvil-head of the movable jaw the two jaws are set into the wood and made to grasp the nail-head, as shown 55 in Fig. 3. Then the claw of a hammer is entered into the claw-hammer hold, as indicated in Fig. 3. Then by pulling backward on the hammer-handle, as shown in Fig. 4, the nail is partially extracted. The remainder of the extraction is accomplished by the direct application of the claw of the hammer to the nail.

I claim as my invention—

1. In combination, the frame composed of two correspondingly-shaped parts, the fixed jaw riveted between and to the two parts of the frame, the filling-piece riveted between and to the two parts of the frame, the anvil-headed movable jaw pivoted between and to the two parts of the frame, and the two pins projecting laterally from the two sides of the movable jaw, all substantially as described.

2. In combination, the frame composed of two correspondingly-shaped parts, the fixed jaw riveted between and to the two parts of the frame, the foot-bearing filling-piece riveted to and between the two parts of the frame, the anvil-headed movable jaw pivoted between and to the two parts of the frame, and the two pins projecting laterally from both sides of the movable jaw, substantially as described.

EDWARD C. FOWLER.
